UNITED STATES PATENT OFFICE.

ADOLPH LANG AND HARPER F. SMITH, OF PHILADELPHIA, PENNSYLVANIA, ASSIGNEES OF ONE-THIRD TO CHARLES H. ZINK, OF PHILADELPHIA, PENNSYLVANIA.

METHOD OF PRODUCING GAS.

No. 833,400.

Specification of Letters Patent.

Patented Oct. 16, 1906.

Application filed November 22, 1905. Serial No. 283,599.

To all whom it may concern:

Be it known that we, ADOLPH LANG and HARPER F. SMITH, citizens of the United States, residing in the city and county of Philadelphia, Pennsylvania, have invented a new and useful Method of Producing Gas, of which the following is a specification.

In two pending applications, one for an apparatus for producing gas, filed October 23, 1905, Serial No. 283,879, and the other for a lamp, filed October 10, 1905, Serial No. 282,119, we have described and claimed different constructions adapted to produce a new gas.

Our present invention consists of a novel method for producing a gas which produces an intense heat, and when this heat contacts with an incandescent body, such as the mantle of a lamp, a very strong and brilliant light is produced.

In the accompanying drawings we have shown different forms of an apparatus for carrying out our invention.

Figure 1 represents a sectional elevation of an apparatus adapted to produce a gas embodying our invention. Fig. 2 represents a side elevation of the air and gas heating pipes in detached position. Fig. 3 represents a side elevation of Fig. 2. Fig. 4 represents a sectional plan view of Fig. 2. Fig. 5 represents a sectional elevation of another embodiment of an apparatus for producing gas. Fig. 6 represents a sectional plan view of the air and gas heating pipes shown in Fig. 5, but in detached position. Fig. 7 represents a diagrammatical view of another embodiment of an apparatus adapted to carry out our invention.

Similar numerals of reference indicate corresponding parts in the figures.

Referring to the drawings, 1 designates the intake-pipe for the gas, said pipe being contained within an outer air pipe or casing 2, both ends of said casing being sealed or closed in any suitable manner.

3 designates the air-inlet, which is controlled by means of a suitable valve 4.

In Figs. 1 to 4, inclusive, we have shown the air and gas heating pipes as being inclined at an angle to the intake-pipes. The gas entering through the intake-pipe 1 passes into the pipe or conduit 5 leading therefrom. This pipe extends inwardly, as seen at 6,

thence extends outwardly, as seen at 7, thence downwardly, as seen at 8, and thence across, as seen at 9. This pipe then extends upwardly, as seen at 10, outwardly, as seen at 11, downwardly, as seen at 12, across, as seen at 13, upwardly, as seen at 14, inwardly, as seen at 15, thence downwardly, as seen at 16. At 17 it is seen as extending partly across and entering a gas-chamber 18. The air enters through the inlet 3 and passes into the air-chamber 2, thence through the pipe 19 to the gas-chamber 18, as seen at 20. Since this pipe 19 is arranged in a similar manner to the gas-heating pipes, there being four on one side and two on the other, the same being in substantially the form of a horseshoe, as seen in Fig. 3, we have deemed it unnecessary to number and describe the different branches of this pipe, since the same would be similar to the gas-heating pipe. As seen in Fig. 1, in the present instance the outlet for the heated gas is in advance of the outlet for the heated air. The heated air and gas in the gas-chamber 18 unite therein to form a separate and distinct gas and also in the chamber 21, which forms a continuation of the gas-chamber 18. The gas passes thence to the incandescent mantles, which may be supported in any suitable manner.

22 designates a funnel or an inverted cone, which serves to deflect the radiant heat from the mantles against the air and gas heating pipes. The globe 23 is supported in any suitable manner, such as that shown in Fig. 1, the globe being supported in a bracket 24, adjustably secured to a lug 25, extending downwardly from the casing of the chamber 21.

26 designates a casing surrounding the funnel 22 and having secured at its lower end by any suitable means a reflector 27, and between this and the globe 23 is a suitable collar or ring 28.

29 designates the top casing, secured at the upper end of the device and surrounding in the present instance the intake-pipes.

30 designates a supporting-bracket engaging the top casing 29 and the outer casing 26. In the embodiment shown in Figs. 5 and 6 we have shown a slightly-modified form of apparatus, in which separate air and gas intake pipes are employed, said pipes being placed substantially horizontally above the

mantles and the heated gas enters the oxidizing-chamber slightly in rear of the inlet for the heated air. In this embodiment 31 designates the intake-pipe for the gas, provided with a suitable controlling-valve, said pipe extending outwardly at its lower end, as seen at 32 in Fig. 6, and then extending inwardly across, as seen at 33, then being bent upon itself, as seen at 34, and entering the gas-chamber 35, as seen at 36.

37 designates the intake-pipe for the air, which is also provided with a suitable controlling-valve, said pipe being bent outwardly, as seen at 38, in a direction opposite from the pipe 32. This pipe 38 then passes across to the other side, as seen at 39, and bends rearwardly, as seen at 40, entering the gas-chamber 35, as seen at 41, in advance of the inlet for the heated gas. The heated air and gas unite in the gas-chamber 35 and the chamber 42, which is a continuation thereof. The gas formed by this union then passes to the mantles, as may be readily understood from our prior applications hereinbefore referred to. In this embodiment it will be seen that the apparatus is similar to that shown in Figs. 1 to 4, inclusive, except that separate intake-pipes are employed and that the air and gas heating pipes are arranged at a different angle to the mantles.

In the apparatus shown in Fig. 7 the gas enters through the pipe 43 and passes into the coil-heating pipe 44, thence into the chamber 45.

46 designates an air-compressing device, by means of which the air is compressed and forced through the valved conduit 47 and through the coil 48, which opens into the gas-chamber 45.

49 designates a baffle-plate extending into the chamber 45.

50 designates burners suitably connected with the chamber in which new gas is formed and adapted to heat the gas-conduit 44 and the air-conduit 48.

51 designates a valved conduit leading from the chamber in which the new gas is formed to a lamp or to any desired point of utilization.

50 In Fig. 1 we have shown the inlet for the heated gas in the chamber in which the union takes place as being in advance of the inlet for the heated air. In Fig. 5 the inlet for the heated gas in the chamber in which the union takes place is shown as being in rear of the inlet for the heated air in the said chamber, and in Fig. 7 these two inlets for the heated air and gas in said chamber are shown as being adjacent to each other and substantially in the same plane. It is further to be noted that in all the embodiments the proportion of air employed is much greater than the amount of hydrocarbon gas which is used.

In carrying out our invention the air and

65 gas are led through separate conduits into

the chamber in which the union takes place. These air and gas heating conduits are located adjacent a suitable source of heat in any desired manner, and the heat which is produced by separate burners or by heat radiating from the mantles, such as is shown in the lamp seen in Figs. 1 and 5, causes the separate air and gas conduits to be highly heated, so that the air and gas passing therethrough also become heated to such a degree that when they come into contact with each other in a separate chamber they instantly unite to form a separate and distinct gas, it being understood that the proportion of air employed is always greater than the proportion of gas. By reason of preheating both the vapor and the air on their introduction into a separate chamber the heated products instantly unite and produce a new gas, which numerous analyses by an expert chemist resulted as follows: carbonic acid, 0.80 per cent.; oxygen, 17.80 per cent.; carbon monoxid, 5.82 per cent.; hydrogen, 3.72 per cent.; methane, 2.68 per cent.; nitrogen, 69.18 per cent.; total, one hundred per cent. For this reason we call the chamber in which this union takes place a "gas-chamber," in which the separately-preheated products form a new gas. It will be seen from this analysis that there is present a very high percentage of oxygen, with the percentage of hydrogen very low, as is also the percentage of inert carbonic acid, and it will be apparent to those skilled in this art that an intense heat will be generated, owing to the percentage of hydrogen and oxygen present. The air may be admitted to the pipes or conduits either under its normal atmospheric pressure or it may be compressed to any desired degree by means of any suitable or conventional type of air-compressor and then led through the air-heating conduits to a separate chamber, where it unites in its highly-heated state with the heated gas to produce the desired gas.

In carrying out our method we proceed as follows: The controlling-valve in the gas-conduit is opened, and simultaneously therewith the controlling-valve in the air-conduit is opened. The air and gas will now pass through the conduits to the burners, which are now ignited by any suitable means. The air and gas conduits will be heated by the heat coming directly from the burners or radiated from the mantles, and the separately-heated air and gas will come into contact with each other in a separate chamber and immediately unite to form a specific and fixed gas. A distinct gas will also be produced if only the gas-conduit is heated and the heated gas led into a separate chamber, where it comes into contact with the air under pressure entering therein.

In the broad scope of our invention it is immaterial in what manner the air and gas heating conduits are arranged with respect to

130

the source of heat or whether the source of heat is derived from the lamp itself or from any external source. This gas after it has been produced may be led to any desired point of utilization, such as a lamp or burner, as shown in Fig. 7. It will thus be seen that in the broad scope of our invention the hydrocarbon gas is separately heated and air under pressure is separately heated. The new gas thus formed gives a very intense heat and produces a very brilliant light when brought into contact with an incandescent body, such as the mantle of a lamp. The gas thus produced may be led to any desired point of utilization without any deterioration in its lighting or heating properties, because when the two heated gases unite their affinity for each other causes the product thus formed to become a fixed product, which on cooling remains absolutely unchanged and has precisely the same properties as when in a heated condition.

Having thus described our invention, what we claim as new, and desire to secure by Letters Patent, is—

1. The method of producing a new gas which consists of separately superheating air under pressure and a hydrocarbon gas and then leading the heated air and gas into a

chamber wherein the heated air and heated gas unite to form a separate and distinct gas. 30

2. The method of producing gas which consists of superheating a hydrocarbon gas, leading this gas in its heated condition into a chamber and simultaneously therewith leading into said chamber air under pressure which unites with the heated gas to form a separate and distinct gas. 35

3. The method of producing gas which consists of compressing air to a desired degree, leading this air through a conduit, superheating this conduit, leading the heated air into a chamber and simultaneously leading a superheated gas into said chamber to unite with the heated air under pressure to 45 form a separate and distinct gas. 40

4. The method of producing a gas which consists in superheating air under pressure and separately heating a hydrocarbon gas, leading the heated air and heated gas into a 50 chamber wherein they unite, and then highly heating the product of the union in said chamber.
